(57) **CLAIM**

The ornamental design for display screen with animated graphical user interface, as shown and described.

DESCRIPTION

FIG. 1 is a first image in a sequence for a display screen with animated graphical user interface showing a first embodiment of our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof; and

FIG. 11 is an eleventh image thereof.

FIG. 12 is a first image in a sequence for a display screen with animated graphical user interface showing a second embodiment of our new design;

FIG. 13 is a second image thereof;

FIG. 14 is a third image thereof;

FIG. 15 is a fourth image thereof;

FIG. 16 is a fifth image thereof;

FIG. 17 is a sixth image thereof;

FIG. 18 is a seventh image thereof;

FIG. 19 is an eighth image thereof;

FIG. 20 is a ninth image thereof;

FIG. 21 is a tenth image thereof; and,

FIG. 22 is an eleventh image thereof.

The appearance of the animated graphical user interface sequentially transitions between the images shown in FIGS. 1-11 according to the first embodiment and the images shown in FIGS. 12-22 according to the second embodiment. The process or period in which one image transitions to another forms no part of the claimed design.

The portions of the drawings shown in broken lines represent the display screen and portions of the graphical user interface and form no part of the claimed design.
